COAT

Johanna P. Schweiss, Webster Groves, Mo., assignor to
The Grove Company, St. Louis, Mo., a corporation of Missouri

Filed Oct. 13, 1965, Ser. No. 87,449

Term of patent 14 years

(Cl. D3—4)

The characteristic features of my design reside in the combination on a coat of a back pocket on the skirt portion and a chevron line across the back between the waist and skirt portions, together with a round collar at the neck, a zip fly front, and U-shaped pockets on either side of the front that open at the side seam all as shown on the drawing.

I claim:

The ornamental design for a coat as shown and described.
